UNITED STATES PATENT OFFICE.

HARRY L. ALLSPAWE, OF WEST LAFAYETTE, INDIANA.

GAME.

Application filed April 9, 1923. Serial No. 630,895.

To all whom it may concern:

Be it known that I, HARRY L. ALLSPAWE, a citizen of the United States, residing at West Lafayette, in the county of Tippecanoe and State of Indiana, have invented 5 certain new and useful Improvements in a Game, of which the following is a specification.

The present invention relates to an amusement device and more particularly to a game which has for its principal object to provide amusement for youngsters ranging from the ages of about six to twelve years.

A particular object of the invention is to provide a simple apparatus which may be manufactured cheaply yet be durable and reliable.

The game is played similar to the ordinary game of basket ball but contemplates 20 bringing the apparatus within the ability of the youthful both physically and financially.

With the above and numerous other objects in view as will appear as the description progresses, the invention resides in certain novel features of construction, and in the combination and arrangement of parts 25 as will be hereinafter more fully described and claimed.

30 In the drawing—

Figure 1 is a rear elevation of the apparatus,

Figure 2 is a top plan thereof,

Figure 3 is a perspective of the basket supporting device, and

Figure 4 is a detail section taken substantially on the line 4—4 of Figure 2 looking in the direction of the arrow.

Referring to the drawing in detail it will 40 be seen that the apparatus consists of a backboard and a basket supporting element mounted thereon.

The backboard includes a frame 1 substantially rectangular in formation and provided on its rear faces at its corners with buffers 2. The top of the frame is provided with eye screws 3 so that the same may be hung upon nails or the like so as to lie against a wall, the buffers engaging the 45 wall so as to prevent injury thereto. A

cover 4 is provided on the forward face of the frame and may be made of any suitable material such as boxboard, cardboard or the like. A beam 5 is secured in the frame behind the cover 4 and is preferably constructed of wood or some other suitable strong material so that the basket supporting device may be secured thereto through the cover 4. The beam 5 is situated in close proximity to the lower side of the frame 1. 55

The basket supporting member includes a hoop 6 which terminates in a pair of parallel abutting arms 7 which radiate outwardly therefrom and terminate in the depending diverging legs 8 the terminals of 65 which are provided with eyes 9. These legs 8 are disposed at right angles to the arms 7 and the arms 7 are disposed coplanar with the plane of the hoop 6. Bolts 10 secure the eyes 9 to the beam 5 and U-bolts 11 engage 70 the legs 8 adjacent the arms 7 and secure them to the beam 5. Thus the basket holding device is properly braced and the mesh basket 12 is secured to the hoop 6 in the usual manner. 75

The disclosure of my invention which I have made in detail herein relates only to the preferred structure thereof and it is to be understood that numerous changes may be made without departing from the scope 80 of the invention or sacrificing any of the advantages thereof.

Having thus described my invention what I claim as new is:—

In a game apparatus, a backboard, a basket supporting device including a hoop, arms radiating from the hoop, legs depending from the arms and diverging from each other, the extremity of the legs terminating in eyes, bolts passing through the eyes and the backboard, and U-bolts passing through the backboard and engaging the legs adjacent the arms. 85 90

In testimony whereof I affix my signature in presence of two witnesses.

HARRY L. ALLSPAWE.
